MAGAZINE MULTIPLE TOOL HANDLE

James E. Egan, Waukesha, Wis.

Application December 5, 1949, Serial No. 131,201

6 Claims. (Cl. 145—63)

1

The invention relates to a multiple tool. The object of the invention is to provide a multiple tool in which a plurality of tools are housed within the handle of the tool, and any one of the tools may be selectively projected into its operating position relative to the handle. Thus the tool may carry a series of different kinds of screwdrivers or wrenches of different type and sizes any one of which may be quickly made available for use.

A further object of the invention is to provide a tool having a multiple tool housing handle, mechanism associated with the handle for selectively moving any one of the tools into operating position relative to the handle, and means for locking the tool in its operating position.

The invention further consists in the several features hereinafter described and more particularly defined by claims at the conclusion hereof.

In the drawings,

Fig. 1 is a vertical sectional view of a tool embodying the invention, the parts being shown in a tool selector position;

Fig. 2 is a view similar to Fig. 1 showing the parts in an operative position;

Fig. 3 is a detailed horizontal sectional view taken on the line 3—3 of Fig. 2;

Fig. 4 is an elevation view of the tool;

Fig. 5 is an elevation view of the tool retainer and guide;

Fig. 6 is a detailed front elevation view of certain of the parts;

Fig. 7 is a side elevation view of the indexing means for the tool selector;

Fig. 8 is a plan view of the part shown in Fig. 7;

Fig. 9 is a detailed top view of one of the tools;

Fig. 10 is a vertical sectional view similar to Fig. 1 showing a modification;

Fig. 11 is a vertical sectional view similar to Fig. 2 of the modified form shown in Fig. 11;

Fig. 12 is a detailed view of parts of the modification;

Fig. 13 is an elevation view of the modified form of tool.

Referring to Figs. 1 to 8 of the drawings, the numeral 10 designates the handle of the tool which is hollow to form a housing for the tools 11, each of which has a polygonal shank 12, here shown as a hexagon, which in the operative position of the tool registers with a similarly formed polygonal opening 13 in the lower end of the tool which prevents rotation of the positioned tool relative to the handle. As shown,

2

the handle 10 has a bore 14 to which radially disposed longitudinally extending tool spacer ribs 15 are secured or formed integral therewith, if desired. The upper end of the handle has an annular groove 10a to receive a spring retainer ring 16, and it has a tapered bore portion 14a to guide the lower ends of the tools to the chuck opening 13.

A rotatable tool retainer 17 is formed as a tube provided with spaced annular flanges 18 and 19 near its upper end, said tube being split throughout its length by a series of connecting slots 20, 21, 22, 23, and 24. The upper flange 18 of this tube rests on the tops of the ribs 15 so that the tube may be rotated relative to the housing. Each tool 11 has a notch 25 formed in its upper end and is cut back or relieved at the top side 26 of this notch so that the tools may be hung from or held against longitudinal movement by the flange 19 by the engagement of the notched portion 25 with said flange. The aligned slots 21, 22, and 23 permit successive placement of the tools on the retainer which also forms a guide for the tool selector and positioning mechanism.

A tool indexing member 27 comprises a flanged metal disk which has a conically inclined top edge 28 engageable with the ring 16 and adapted under end thrust to exert pressure against said ring. This disk has a central opening 29 to fit over the upper end of the tube 17 with a slot 30 in its top extending through the upper conical edge 28. The side flange 31 of the disk in line with the slot 30 has a depending finger 32 provided with an index point 32a. The top of the disk adjacent portions of the opening 29 has slits 33 cut therein communicating with slits 34 adjacent the slot 30, these slits 34 also extending down through the side flange of the disk as shown in Fig. 7. The disk is made of spring steel so that the finger 32, because of the slitting, forms a spring finger which extends down into the slotted portion of the flange 13 of the tube so that it is keyed to said tube. The bottom edge of the flange 31 rests on the flange 18 of the tube.

The tool selector and positioning mechanism includes a round rod 35 having a lever slot 36 extending the length thereof with a transverse notch 37 intersecting said slot near its upper end which is provided with a bore 38 in which a rod 39 is slidably mounted. The rod 39 has a lever slot 40 alining with slot 36 and also carries a push button or plunger head 41 and has one end of a spring 42 anchored thereto.

A selector lever 43 is mounted to move in the slots 36 and 40 and has a locking and pivot pin 44 mounted in it intermediate its ends, said pin being disposed in the notch 37 when the lever is in a withdrawn position as shown in Fig. 1, it being noted that the rod 39 is slotted at 45 so the movement of the rod 39 relative to rod 35 does not affect said pin, but the lower end of the slot 45 may engage the pin 44 to limit the upward movement of said rod 39. The lever 43 pivots on the rod 35 through the pin 44 and is connected to the lower pin end 46 of the spring 42 by a slot 47. At its lower end, the lever 43 has a forked selector block or chucking means 48 pivotally connected thereto by a pin 49. The block 48 is provided with a notched head 50 for chucking engagement with the notched portion 25 and side 26 of a selected tool, it being noted that in Fig. 1 the block 48 is disposed in the slot 21 so that the selected tool is not engaged by the flange 19. The upper end of the lever has a cam or wedge surface 51 which is adapted to engage a transversely disposed portion 52 (see Fig. 6) of the spring to be forced by said spring into the position shown in Fig. 1 with the pin 44 in the notch, the spring 42 then acting on the lever to swing its lower end outwardly so that the selector block or chucking means 48 together with the whole selector assembly and the retainer 17 and indexing member 21 may be turned as a unit to position the selector lever 43 and the block or chucking means 48 in proper radial position relative to the tool that the operator desires to use. The retainer 17 turns with the lever 43 because said lever is keyed to said member by its sliding mounting in the slot 20 of said member. The member 21 is in turn keyed to the retainer 17 by the projection of the finger 32 into the slot 21 of said retainer, it being noted that as the retainer is turned, the finger 32 rides over the tops of the tools and in any indexed position its point 32a moves down into registry with a notch 53 (see Fig. 9) formed in the top of the tool.

With the selector lever 43 positioned over the tool to be operatively positioned in the holder or handle 10 and the parts then being in the position shown in Fig. 1, the operator presses inwardly on the button 41 moving rod 39 inwardly relative to rod 35 and moving spring 42 inwardly or downwardly relative to lever 43 causing said lever to pivot about the pin 49 and its upper end to swing outwardly. A washer 54 on the rod 39 engages rod 35 relaying thrust to pin 44 to lever 43. There is then a direct thrust on the lever 43 from the rod 39 and the selected tool held in selector block or chucking means 48 is pushed downwardly in the handle 10 until its lower end is guided by the taper bore 14a into the chuck opening 13, the spring 42 permitting the lever 43 to shift relative to the rod 35 so that while the pin 44 may be almost out of the notch 37 after engagement of washer 54 with the rod 35 when the tool 11 is extending through the opening 13, the lever 43 is moved down until the ends of the pin 44 engage the top of the tube 41, and under these conditions since the ends of this pin are bevelled as shown at 55 in Fig. 6, they will act to cam the upper end of the lever inwardly and permit the pin 44 to move down into the tube until the polygonal shank of the tool registers with the opening 13, and at the completion of the movement of the selector mechanism, the pin 44 aligns with the slot 22 in the retainer 17 which permits the spring 42 to throw the upper end of said lever 43 outwardly to dispose the pin 44 in a

position of abutting engagement with the flange 19 adjacent said slot so any end thrusts imparted against the tool will now be resisted through the selector mechanism transferring these thrusts through the pin to the members 17 and 27 to the retainer ring 16 and then to the handle, the greater the thrust, the greater the wedging action of the ring 16 because of the tapered surface 28.

With the parts shown in the position of Fig. 2 when the operator pulls outwardly on the button 41, the spring 42 shifts its position in the slot 47 and acts on the lever 43 to shift the pin 44 into the notch 37 and out of locking engagement with the flange 19, and then a continued pull on the button 41 brings the parts to the initial position shown in Fig. 1 where the selector may be turned to engage another tool, if desired. The handle 10 is provided with index marks 56 to aid in positioning the selector lever 43 and the indexing finger 32 relative to the tools in said handle. It will be noted from the above that the lever 43 with the pin 44 forms a latch to lock the selector mechanism in a tool positioning position and that this latch is released through the relative movement of the rods 35 and 39.

Referring to Figs. 10 to 13 which show a modified form of the invention, the handle of the tool is formed of telescoping cylinders 57 and 58. The cylinder 57 is generally similar to the handle 10 and has a bore 59 to which radially disposed longitudinally extending tool spacer ribs 60, similar to the ribs 15 are secured or formed integral therewith, if desired. The upper end of the cylinder 57 has an annular groove 61 to receive a split spring ring retainer 62, and it has a tapered bore portion 59a to guide the lower end of the tools 41 having polygonal shanks 42 to the similarly shaped chuck opening 62.

The cylinder 58 has a bore 63 which is slidably mounted on the outer side of the cylinder 57, and it fixedly carries a toothed chuck plate 64 at its upper end adapted to engage in the toothed end portion 65 of the cylinder 57 so that both parts of the handle will turn together in the operative position of the tool as shown in Fig. 11.

A tool retainer 66 is formed as a tube provided with spaced annular flanges 67 and 68 at its upper end, said tube being split throughout its length by a slot 69 similar to the slot 21. The upper flange 67 of this tube rests on the tops of the ribs 60. The tool 11 is the same as in the first described construction having a notch 25 formed in its upper end and is cut back or relieved at the top side 26 of this notch so that the tools may be hung from or held against lengthwise movement by the flange 68 by the notched portion 25 engaging with said flange.

A tool indexing member 70, identical with the member 27 except that its top is not tapered or inclined, is interposed between the carrier 66 and the ring 62, and it has a central opening 71 and a slot 72 communicating therewith similar to the opening 29 and slot 30 of member 27.

The tool selector and positioning mechanism includes a post or abutment 73 and a spring finger 74. The post 73 is anchored to the top of the cylinder 58 by a screw 73a and has a tapered side 75 against which the lower end of the spring finger 74 abuts in the operative position of the tool and has a stop flange 75a at its lower end to engage at one side with a stop projection 76 on the member 66 to limit the outward movement of the cylinder 58 and is slotted at its opposite side to form a guide for the finger 74, this slot not being shown but being indicated

in Fig. 11 of the drawings by the fact that the flange 15a projects over a part of the finger.

The spring finger 74 is anchored at its upper end to the post 73 by screws 77 and is formed to normally extend outwardly at 78 from the post 73 and also to have a notched lower end or chucking means 79 adapted to interlock with the notched portion 25 of the tool 11 and be under some tension in the position shown in Fig. 10. As in the first described construction, rotation of the cylinder 58 moves the finger 74 with it so that said finger may be positioned over any tool desired for use, the index member 70 and the member 66 also being rotated because the post has a keyed connection with the top portion 80 of the member 66 and a similar connection with the slot 72 of the indexing member 70.

Rotation of the cylinder 58 and the movement of the finger 74 to a position to engage the desired tool is permitted when the cylinder 58 is drawn out to the position shown in Fig. 10. Then as the cylinder 58 is pushed in or over the cylinder 57, the tapered portion 59a acts to cam or guide the tool 11 into the opening 62, so that its polygonal end seats itself in said opening and in doing so draws the notched end or chucking means 79 of the spring finger 74 into abutting engagement with the post 73 as shown in Fig. 11 in the final position of the tool as shown in Fig. 11. In this position the pressure of the spring finger 74 on the tool acts to hold the tool against movement in the cylinder 58, and as the operator in using the tool has to exert pressure on the cylinder 58 to engage the tool with the work, the tool will be held against longitudinal movement relative to the cylinder 57, and since the keyed or clutch connection 64, 65 is then engaged, the tool 11 is turned by the turning of the assembled parts by exerting a turning action on the cylinder 58. It will be noted that in this form the cylinder 58 with the parts 73 and 74 forms a rotary and lengthwise movable tool selector and positioning mechanism for positioning a selected tool in operative position in the opening 62 of the handle portion 57 and holding it against endwise movement relative to said handle.

It is also to be noted in connection with the first form above described that by pressing inwardly on the push button 41 so as to bring it into abutting engagement with the rod 35 in the extended position of the device as shown in Fig. 1 and then pushing inwardly on the lower end of the lever 43, this lever may be disconnected from the tool 11 in its selective position so that this selected tool may be dropped out of the housing through the opening 13 and will permit pulling out the selector assembly including the rod 35 and lever 43 from the housing and clutching the lever 43 with a new tool and then reassembling the parts 35 and 43 in the housing with the clutched tool in the position of assembled relation shown in Fig. 1 with the new tool interlocked with the block 48.

It is to be noted that in either form of the device the tool 11 is always positively chucked to the selector mechanism either in its withdrawn position as shown in Figs. 1 and 10 or in its operative position as shown in Figs. 2 and 11.

The tools 11 may be of various kinds, for example, plain screwdrivers, screwdrivers for Phillips head screws, screw wrenches for Allen head screws, chisels, gouges, gimlets, etc.

I desire it to be understood that this invention is not to be limited to any particular form or

arrangement of parts except in so far as such limitations are included in the claims.

What I claim as my invention is:

1. In a multiple tool, the combination of a handle forming a radially partitioned housing for a plurality of tools and provided with an opening at one end to operatively receive the shank of any one of said tools, said tools having notched shanks, a retainer having a flange engaging the notched shanks of said tools and mounted for rotary adjustment in said handle relative to said tools with a slot in said flange to free any selected tool therefrom, selector means for rotating said retainer including a chucking means working in the slot of said flange to positively engage the selected tool, said selector means also mounted for reciprocatory movement relative to said handle to positively move the selected tool from its position in the slot in said flange into operative position in said opening, and means for locking said selector means against endwise movement relative to said handle when the selected tool is in operative position.
2. In a multiple tool, the combination of a handle forming a radially partitioned housing for a plurality of tools and provided with an opening at one end to operatively receive the shank of any one of said tools, said tools having notched shanks, a retainer having a flange engaging the notched shanks of said tools and mounted for rotary adjustment in said handle relative to said tools with a slot in said flange to free any selected tool therefrom, an indexing ring mounted on said retainer and rotatable therewith and having an inclined edge, a retainer ring mounted in said handle and engageable with said inclined edge, and rotary and reciprocatory tool selector mechanism rotatable with said retainer and movable lengthwise relative thereto to move a selected tool into an operative position relative to said opening in said handle and having releasable locking means engageable with said retainer in the operative position of the selected tool.
3. The structure as defined in claim 2 in which the selector mechanism includes a pair of relatively slidably movable rods provided with aligned lengthwise extending slots, one of said rods having a transversely disposed notch, a lever working in said slots and provided with a pin engageable in said notch, the other of said rods provided with a hand grip and having a spring anchored at one end thereto, said spring at its other end having a lost motion connection with said lever and having a transversely disposed portion engageable with a wedge surface at one end of said lever, the other end of said lever operatively carrying a notched selector block engageable with the notched end of any one of the selected tools, the pin on said lever engageable with said retainer in operative position of the tool to releaseably lock the tool against endwise movement in said handle.
4. In a multiple tool, the combination of a handle forming a radially partitioned housing for a plurality of tools and provided with an opening at one end to operatively receive the shank of any one of said tools, said tools having notched shanks, a retainer having a flange engaging the notched shanks of said tools and mounted for rotary adjustment in said handle relative to said tools with a slot in said flange to free any selected tool therefrom, selector means for rotating said retainer including a chucking means working in the slot of said flange to posi-

tively engage the selected tool, said selector means also mounted for reciprocatory movement relative to said handle to positively move the chucked selected tool from its position in the slot in said flange into operative position in said opening.

5. A multiple tool, as defined in claim 4, in which the selector means includes a post and a tool head engaging spring finger engageable with a selected tool and adapted to abut said post in the operative position of the selected tool.

6. In a multiple tool, the combination of a handle forming a radially partitioned housing for a plurality of tools and provided with an opening at one end to operatively receive the shank of any one of said tools, said tools having notched shanks, a retainer having a flange engaging the notched shanks of said tools and mounted for rotary adjustment in said handle relative to said tools with a radially disposed slot in said flange to free any selected tool there-

from, selector means for rotating said retainer including an oscillatory lever provided with a chucking means working in the slot in said flange and engageable with the notched shank of the selected tool to positively hold said tool, said selector means also mounted for reciprocatory movement relative to said handle from a tool selector position to a position in which the selected tool is positioned in the opening in said handle, said chucking means in its tool selector position being releaseable from said selected tool on the manual operation of said lever.
